UNITED STATES PATENT OFFICE.

JULIUS GRABER, OF NEW YORK, N. Y.

TRANSFER MECHANISM FOR CALCULATING-MACHINES.

1,022,840.

Specification of Letters Patent.

Patented Apr. 23, 1912.

Application filed December 15, 1911. Serial No. 665,902.

To all whom it may concern:

Be it known that I, JULIUS GRABER, a citizen of the United States, residing at New York city, county and State of New York, have invented a new and Improved Transfer Mechanism for Calculating-Machines, of which the following is a specification.

This invention relates to an improved transfer mechanism for calculating machines and more particularly to novel means for locking such mechanism in position. The transfer mechanism is of the kind described in Patent #972,360 granted to me June 30th, 1910 and in a co-pending application filed by me October 21st, 1911 under Serial No. 655,953. This transfer mechanism comprises essentially a finger coöperating with a ciphering mechanism, which finger is brought into alinement with a toothed wheel coöperating with the adjoining ciphering mechanism whenever the transfer is to be made for the purpose of performing the desired carrying or borrowing of tens, hundreds, etc., as fully disclosed in the above citations.

The present invention provides novel and effective means for preventing an accidental displacement of the finger so as to insure its engagement with the coöperating toothed wheel.

In the accompanying drawing: Figure 1 is a plan of part of the transfer mechanism provided with my improved locking means; Fig. 2 a cross section on line 2—2, Fig. 1; Fig. 3 a cross section on line 3—3, Fig. 1, showing the parts in a different position; Fig. 4 a section through the retaining latch on line 4—4, Fig. 2, and Fig. 5 an enlarged plan of part of Fig. 1, showing the parts in a different position.

Upon a squared shaft 10 is mounted a relatively fixed toothed sector 11 which receives rotary motion through a miter wheel 12 and transmits said motion to the ciphering mechanism proper. Upon shaft 10 is slidably and non-rotatably mounted a mutilated barrel 13 that coöperates with a scalloped rotary disk 14 thereby preventing the latter from accidentally rotating, while the parts 13, 14 are in operative engagement. Barrel 13 is provided with a grooved hub 15 which is engaged by a fork 16 rigidly secured to an axially reciprocable rod 17. The latter is recessed as at 18 for the reception of one end of a spring-influenced shifting lever 19, the other end of which is en-

gaged by a trigger 20. Hub 15 is provided with a radial transfer finger 21 and with a helical cam 22 adapted to be engaged by a fixed abutment 23. Finger 21 is adapted to mesh into a toothed wheel 24 coaxially mounted with disk 14.

Whenever during the course of operation of the machine, motion is to be transferred from shaft 10 to that of wheel 24, trigger 20 is swung toward partition 25, so as to tilt lever 19 and thereby move rod 17 backward (Fig. 1). Thus fork 16 will cause barrel 13 to participate in this movement, whereby barrel 13 is withdrawn from underneath scalloped disk 14 while finger 21 is brought into alinement with gear wheel 24, all as fully described in my above cited patent and co-pending patent application.

As the parts hereabove referred to are liable to be subjected to comparatively severe shocks during the operation of the machine, which shocks might tend to dislodge said parts, means are provided for positively preventing a return of barrel 13 and finger 21 to their original positions until a meshing between said finger and wheel 24 has taken place, thereby insuring a reliable operation of the transfer mechanism. These means are shown to consist of a latch 26 having a hub or sleeve 27 that is free to oscillate on a headed stud 28 secured to partition 25 by a screw 29. Latch 26 is perforated as at 30 for the reception of one end of a coiled spring 31, the other end of which is secured to a pin 32 extending outward from stud 28 through corresponding slots 33 of sleeve 27, said pin also serving to limit the play of the latch. The latter rests normally on the unmutated section of barrel 13, but as soon as the latter has been shifted backward for transferring purposes, latch 26 slips off the barrel owing to the action of spring 31, thereby temporarily locking the barrel against return movement.

The relative position of the parts is such that prior to and during the engagement of finger 21 with wheel 24, latch 26 is located in front of the forward edge of the unmutated section of barrel 13, so as to prevent the latter from moving forward. As soon as the engagement between the parts 21, 24 has taken place, the mutilated section 34 of barrel 13 will have arrived opposite latch 26, so that cam 22 in engaging abutment 23 can unobstructedly shift barrel 13

forward. Thus during the last stage of the rotation of the barrel, the latch will ride up on the edge 35 thereof, thereby returning the parts to their original positions.

5 I claim:

1. In a device of the character described, a rotatable shaft, a transfer finger slidably mounted thereon, means for shifting said finger on said shaft, and means for locking 10 the finger against return to its initial position.
2. In a device of the character described, a rotatable shaft, a transfer finger slidably mounted thereon, means for shifting said 15 finger on said shaft, and a latch for locking the finger against return to its initial position.
3. In a device of the character described, a rotatable shaft, a mutilated barrel slidable 20 thereon, a transfer finger carried by the barrel, means for shifting the barrel on the shaft, and a latch cooperating with said barrel.
4. In a device of the character described,

a rotatable shaft, a mutilated barrel slidable 25 thereon, a transfer finger carried by the barrel, means for shifting the barrel on the shaft, and a spring-influenced latch coöperating with said barrel.

5. In a device of the character described, 30 a rotatable shaft, a mutilated barrel slidable thereon, a transfer finger carried by the barrel, means for shifting the barrel on the shaft, a fixed stud, and a spring influenced latch oscillatively mounted thereon and adapted to be engaged by the barrel.

6. In a device of the character described, 35 a rotatable shaft, a mutilated barrel slidable thereon, a transfer finger carried by the barrel, means for shifting the barrel on the shaft, a fixed stud, a spring-influenced latch oscillatively mounted thereon and adapted to be engaged by the barrel, and means for limiting the stroke of the latch.

JULIUS GRABER.
